UNITED STATES PATENT OFFICE.

DAVID BROOKS, JR., OF PHILADELPHIA, PENNSYLVANIA, ASSIGNOR TO THE ELECTRIC CABLE CONSTRUCTION AND MAINTENANCE COMPANY, OF PENNSYLVANIA.

COVERING FOR ELECTRIC WIRES.

SPECIFICATION forming part of Letters Patent No. 437,913, dated October 7, 1890.

Application filed November 7, 1889. Serial No. 329,564. (No specimens.)

To all whom it may concern:

Be it known that I, DAVID BROOKS, Jr., a citizen of the United States, residing in the city and county of Philadelphia, State of Pennsylvania, have invented a new and useful Improvement in Protective Coverings for Electric Wires and Cables, which improvement is fully set forth in the following specification and accompanying drawings.

10 My invention relates to improvements in coverings for electric cables; and it consists in providing the wires with a covering composed of a double layer of tin-foil having between them an adhesive oil, the adjacent 15 edges of each of the layers overlapping.

Figure 1 represents a side elevation of an electric cable covered in accordance with my invention, the layers constituting the covering being partly unwrapped. Fig. 2 represents an end sectional view thereof.

Similar letters of reference indicate corresponding parts in the two figures.

Referring to the drawings, A designates a bunch of insulated wires, which may be bound together by braid or tape, so as to prevent separation of the same. The cable as produced is now saturated with a molten or liquid insulating compound and then wrapped with tin-foil or thin metallic tape or ribbon B, 25 having its adjacent edges overlapping, after which the wrapping is coated with a hot or liquid compound of an adhesive nature—such as rosin and rosin-oil or asphaltum and oil, &c.—of such character that while preventing the separation or parting of the layers will permit them to move or slide upon each other, and a second wrapping C of tin-foil or thin metallic tape or ribbon is wound over the first layer in a similar manner to the 30 first and pressed so that the two layers adhere.

A covering D of braid or tape of fibrous material is then placed over and around the tin-foil, the material being also saturated in a molten or liquid adhesive compound.

Around the braid or material is wound or 45 wrapped a second double layer E F of tin-foil or thin metallic tape or ribbon, after which braid or tape G of fibrous material is wrapped or wound around the layers E F and the surface is painted or otherwise coated with or 50 the whole is dipped in a hot molten or liquid compound—such as asphaltum and oil—the result being a cable having a protective covering of a superior order. It will be seen that as thus covered the cable may be bent in 55 short curves, and while the inner layer may break the outer layer, moving upon itself and the inner layer, will preserve the joints without breaking or opening the same.

Having thus described my invention, what 60 I claim as new, and desire to secure by Letters Patent, is—

1. A cable having a coating with a double layer of tin-foil and an adhesive oil or substance between the said layers permitting the 65 layers to move one on the other without separating or breaking joints, substantially as described.

2. A cable having a covering of a double layer of tin-foil with an adhesive oil between 70 the same, each of the said layers having overlapping adjacent edges and the adhesive oil permitting a sliding movement of the layers on each other without a separation, said parts being combined substantially as described.

DAVID BROOKS, JR.
